UNITED STATES PATENT OFFICE.

ISRAEL HEBERT, OF SYRACUSE, NEW YORK, ASSIGNOR TO THE ELGIN A. SIMONDS COMPANY, OF SYRACUSE, NEW YORK, A CORPORATION OF NEW YORK.

CHAIR.

Application filed July 2, 1923. Serial No. 649,039.

To all whom it may concern:

Be it known that I, ISRAEL HEBERT, a citizen of the United States of America, of Syracuse, in the county of Onondaga, in the 5 State of New York, have invented new and useful Improvements in Chairs, of which the following, taken in connection with the accompanying drawings, is a full, clear, and exact description.

10 This invention relates to a certain new and improved chair.

In the use of chairs, as for instance, dining rooms chairs which are generally of comparatively light weight and structure, great 15 difficulty has been experienced in connecting the seat framework to the rear legs in a sufficiently rigid and strong manner to withstand general use, which in this class of chairs particularly includes the tilting back 20 of the chair by one sitting upon it so that the sole vertical support of the chair is the two rear legs with a lever action of the seat portion upon the joint between it and the said rear legs under the weight of the person 25 sitting upon the chair seat.

For the purpose of meeting that difficulty of providing a chair that will withstand such strains, I have produced the structure of this invention which is peculiarly strong 30 and rigid and at the same time gives an improved appearance to the chair.

Other objects and advantages relate to the details of construction and arrangement of the parts of the chair, all as will more fully 35 appear from the following description, taken in connection with the accompanying drawings in which:—

Figure 1 is a perspective view of a chair of my invention.

40 Figure 2 is a section on line 2—2, Figure 1.

Figure 3 is a fragmentary view illustrating the connection between the sides of the seat framework and the rear legs.

45 The chair illustrated in the drawings of this application comprises in the usual manner front legs —1— and —2—, a seat frame —3—, rear legs —4— and —5— which may be extended upwardly beyond the seat frame 50 and connected by a cross bar —6— to constitute the back of the chair.

55 The particular ornamentation and reinforcement of the various parts of the chair may be of any form and character desired, and constitutes no part of this invention as

the latter relates specifically to the particular connection between the ends —7— and —8— of the seat frame and the respective rear legs —4— and —5— of the chair.

As illustrated, the outer surface of each 60 of the legs —4— and —5— is formed with a cross channel at the proper height for the reception of the ends of the seat framework, these channels being of a suitable depth to receive the flanged extensions —9— formed 65 upon the ends —7— and —8— of the seat frame, the flanged portions —9— being preferably of substantially half the width of the side walls —11— and —12— of the seat frame and of a length substantially 70 equal to the width of the rear legs —4— and —5— of the chair, or the channels —13— in said legs for the reception of the projecting flanges —9— which preferably fit tightly in the channels and form with 75 the outer surface of the rear legs a substantially smooth exterior contour. This interlocking of the seat frame and the rear legs in itself constitutes a rigid engagement between the parts, but my invention includes 80

in addition to such interlocking of the seat frame with the rear legs, the utilization of one or more dowels —14— mounted in the end of the side walls —11— and —12— of the said frame and extending substantially parallel with the flanged portions —9— and spaced therefrom, and of slightly less length than the flanged portions —9— and adapted to fit into a corresponding series of openings, 85 seats, or recesses —15— formed in the rear legs —4— and —5— of the chair adjacent the channels or grooves —13—. By this construction with the flanges —9— seated in the grooves —13— and the dowels —14— seated in the recesses —15— a very strong 90 and rigid engagement is effected between the said frame and the rear legs.

In addition, triangular braces —16— are provided at each corner of said frame and adapted to fit tightly within the corners, four of such braces being provided, one at each corner joint and secured to the respective walls of the said framework as by 100 screws —17—.

As illustrated, the said framework is more or less square in conformation and comprises the two side walls —11— and —12— the rear wall —18— disposed between and connected to the rear legs —4— and —5— respectively, and the front wall —19— disposed between 105 110

and connected to the front legs —1— and —2— respectively.

This particular conformation and structure of seat frame-work is merely illustrative, as are the other features of the chair described, except the particular construction, arrangement and connection between the side walls —11— and —12— of the seat framework and the rear legs —4— and —5— of the chair, and altho I have shown and described a specific construction, form and arrangement of parts, all as illustrative of an embodiment of my invention, I do not desire to restrict myself to the details of the same, as various changes and modifications may be made within the scope of the appended claims.

I claim:

1. In a chair, the combination with a pair of rear legs having grooves extending from front to rear thereof and a plurality of recesses adjacent the grooves, of a seat frame having its side members formed with longitudinally extending flanges seated in said recesses of the legs respectively, and dowels projecting from the ends of the side members and extending substantially parallel with the flanges and seated in the recesses in the legs respectively.
2. In a chair, the combination with a pair of rear legs having grooves extending from front to rear upon the exterior sides thereof, and a plurality of recesses adjacent the grooves, of a seat frame having its side members formed with longitudinally extending flanges of a length substantially equal to the width of the said legs from front to rear, tightly fitting within the respective grooves and being substantially flush with the exterior surface of the respective legs, and dowels extending from the ends of the side members, said dowels being of somewhat less length than said flanges and extending substantially parallel with the flanges and spaced therefrom tightly fitted in the recesses in the respective legs, and triangular bracing means within and secured to the seat frame at the junctures of the seat frame with the rear legs.
3. In a chair, the combination with a pair of rear legs having grooves extending from

front to rear thereof, and a plurality of recesses adjacent the grooves, of a seat frame having its side members formed with longitudinally extending flanges seated in said recesses of the legs respectively, and dowels projecting from the ends of the side members and extending substantially parallel with the flanges, and seated in the recesses in the legs respectively, and triangular bracing means within and secured to the seat frame at the junctures of the seat frame with the rear legs.

4. In a chair, the combination with a pair of rear legs having grooves extending from front to rear upon the exterior sides thereof, and a plurality of recesses adjacent the grooves, of a seat frame having its side members formed with longitudinally extending flanges of a length substantially equal to the width of said legs from front to rear tightly fitting within the respective grooves, and being substantially flush with the exterior surface of the respective legs, dowels extending from the ends of the side members, said dowels being of somewhat less length than said flanges and extending substantially parallel with the flanges and spaced therefrom tightly fitted in the recesses in the respective legs, and triangular bracing means within and secured to the seat frame at the junctures of the seat frame with the rear legs.

5. In a chair, the combination with a pair of rear legs having grooves extending from front to rear thereof, and a recess in each leg adjacent its respective groove, of a seat frame having its side members formed with longitudinally extending flanges tightly fitted in said recesses of the legs respectively, and a dowel extending from each end of the said frame in substantial parallelism with and spaced from the respective flange and tightly fitted in the recess of its respective rear leg.

In witness whereof I have hereunto set my hand this 21st day of June, 1923.

ISRAEL HEBERT.
